UNITED STATES PATENT OFFICE.

STEVEN BURK, OF NEW YORK, N. Y.

CUFF.

1,303,254.

Specification of Letters Patent. Patented May 13, 1919.

Application filed April 3, 1917. Serial No. 159,385.

To all whom it may concern:

Be it known that I, STEVEN BURK, a citizen of the United States, and a resident of the city, county, and State of New York, have invented certain new and useful Improvements in Cuffs, of which the following is a specification.

My invention relates to cuffs for shirts, particularly to folded cuffs, and more particularly to soft folded cuffs. As is the common experience with those who wear soft cuffs, they find that the cuffs soil very easily and I have invented a reversible cuff of the folded type so that the cuffs may be worn longer without being laundered.

In the drawings, similar reference characters represent similar parts.

Figure 1 is the end of a shirt-sleeve provided with my improved reversible soft cuff;

Fig. 2 shows the cuff before it is folded;

Fig. 3 shows the inner face of the cuff, shown in Fig. 2, opened up; and

Figs. 4 and 5 show how the cuff is reversed to bring together the different faces exposed.

In the drawings, A represents a shirt-sleeve; B the normal inner face of the cuff, and C the normal outer face of the cuff before the cuff is folded. In use the cuff is folded on the horizontal line g so that B forms the inner and outer faces of the cuff, while C forms a lining member. This is the ordinary construction of cuff. In my improvement, however, I have made the cuff in the form of a pocket, as shown, for instance, in Figs. 4 and 5, Fig. 4 being a section of Fig. 3. It will be noted that C forms the normal outer face of the cuff before it is folded and B the normal inner face. The cuff is folded near the center at g . The lower portion of the cuff is folded up at g , as shown in dotted lines, and a portion of B then becomes the outer visible portion of the cuff. In order to make a reversible cuff, the members B and C are provided with companion faces D and E, D being the companion face to C, and E, the companion face to B, as shown in Fig. 4. D and E form the lining for the pocket. When it is

desired to reverse the cuff, the faces D and E are turned so as to form the outer faces, thereby changing the faces B and C to the inner faces or linings of the pocket, as shown in Fig. 5. When the cuff is then folded, D becomes the outer visible face of the cuff.

In order that there may be no rough or unfinished edges, I turn in the edges of the faces and stitch them, as shown at the lower ends of Figs. 4 and 5, by stitching h . When the pocket is in its normal condition, as shown in Figs. 1, 2 and 3, in order to prevent the hand of the wearer from catching in the pocket when the hand is passing through the sleeve, I provide the face B with button-holes I adapted to engage with buttons J located on the inner face so as to hold the pocket closed. Each cuff is provided with eight button-holes K for cuff-buttons, four passing through the material plies B and E and four through the plies D and C, arranged as shown in Fig. 3.

As will be readily seen from the drawings and the above description, when one face of the cuff has been soiled, the cuff can be reversed so as to give a clean exposed surface. It is, of course, desirable for various reasons that the folded cuff should always be folded outward, and this is one of the problems which I have solved by my invention, as set forth above.

Having described my invention, what I claim as new and desire to secure by Letters Patent is:

1. In a reversible soft folded cuff, a plurality of plies arranged so as to form a pocket adapted to inclose all but one pair of plies so arranged that any pair of plies may be exposed while inclosing the other plies.
2. In a reversible folding cuff, a plurality of faces arranged in pairs, adapted to form the faces of the cuff, means attaching said faces along the edges thereof to form a pocket, all so arranged that either pair of faces when exposed will form a pocket, inclosed on three edges, for the other faces.

In testimony whereof I have signed my name to this specification.

STEVEN BURK.
